[57] **CLAIM**

The ornamental design for a trolling bar for use with artificial or natural bait, as shown and described.

DESCRIPTION

FIG. 1 is a perspective view of a trolling bar for use with artificial or natural bait, showing my new design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a side elevational view, the opposite side being a mirror image thereof.
